Ernest Merrick

BY

Conrad C. Dillingham ATTORNEY

UNITED STATES PATENT OFFICE.

ERNEST MERRICK, OF ELIZABETH, NEW JERSEY, ASSIGNOR TO AGNES R. MERRICK, OF ELIZABETH, NEW JERSEY, TRADING UNDER THE NAME OF MERRICK FIREPROOF CONSTRUCTION CO., OF ELIZABETH, NEW JERSEY.

FIREPROOF CONSTRUCTION.

1,239,503.

Specification of Letters Patent. Patented Sept. 11, 1917.

Application filed September 9, 1914, Serial No. 860,840. Renewed April 12, 1917. Serial No. 161,673.

To all whom it may concern:

Be it known that I, ERNEST MERRICK, a citizen of the United States, residing at Elizabeth, county of Union, State of New Jersey, have invented certain new and useful Improvements in Fireproof Construction, of which the following is a specification.

My invention relates especially to the construction of fire proof floors and ceilings, but it includes certain features of construction and combinations of parts which may be used in other similar fire proof constructions.

15 One of the objects of my invention is to provide solid metal roofs for the voids in concrete floor construction. Another object is to provide either a concrete or other fire proof ceiling, which forms the bottom boundary of the aforesaid voids.

To attain these and other objects, my invention consists of the features of construction and the combinations of parts herein-after described and claimed.

25 Referring to the drawings which form a part of this specification;

Figure 1 is a perspective view partly broken away of one form of my improved floor and ceiling construction.

30 Fig. 2 is a transverse section partly broken away of a floor construction illustrating one form of my improved wire lath ceiling.

Fig. 3., is a transverse section partly broken away illustrating another form of my improved wire lath ceiling construction.

Fig. 4., is a sectional view through the top of the pan or basket showing the rod and staple constructions.

40 Fig. 5., is an end view, in perspective, partly broken away, of my solid pan or basket, which is used to form the side and upper walls of the voids.

Fig. 6., is a plan view, partly broken away, illustrating the arrangement of metal plate, staples and rods, before it is shaped into the form of a pan or basket.

Fig. 7., is a perspective view of a staple used to secure the rods to the metal basket.

50 Referring to the drawings in which the same reference characters refer to similar parts in the several views, A represents the ordinary "two by four" beams for holding

the temporary floor B, consisting of flooring boards in place to support the concrete 55 construction during its formation. The beams are as usual supported in place by stirrups C secured in the usual way to the I-beams D, 10 indicates the inverted pans or baskets, 11 the rods secured to the basket 60 by staples 12. As hereinafter disclosed, these rods project on either side beyond the basket, as at 13 and 13' and form supporting legs or feet to hold the basket in place so that its lower edges will be elevated the required distance above the temporary floor.

While the pans or baskets 10 can be formed in many ways, they are preferably constructed in the following manner:

When the pans or baskets are to be used 70 in the construction embodying the concrete ceiling 20 Fig. 1., ends 13 and 13' of the rods extend about two inches on either side beyond the edges of the sheet iron pans.

A plate of thin sheet iron of suitable dimensions and preferably about five feet in length and three feet in width, is placed upon an iron table provided with longitudinally hinged leaves. The entire width of the table including the leaves is substantially equal to the width of the plate, and the width of each leaf is substantially equal to one half the width of the center portion of the table. I secure across the plate at intervals of about twelve inches, 85 round steel rods preferably $\frac{1}{4}$ " in diameter by means of several, preferably four rivets to each rod which are of staple construction having a flat head arranged at the bend of the staple. The prongs 14 of the rivets embrace the rods and are bent under the plate to securely keep them in place.

I find that it is necessary to rivet the rods to the plate in the manner described, for in the further construction of the arch, it is necessary that there should be a play, that is; a sliding movement between the rods and the plate. The edges of the plate are then clamped to the leaves, and the plate is then bent by permitting the leaves of the table to drop down into a vertical position. One or both ends of the plate are then folded over the end of the table in the ordinary way in which the extending ends of a paper wrapper are folded around a package in 100 wrapping the same, as indicated by dotted

lines in Figs. 5 and 6. When these are folded, the sides of the pan or basket will normally flare outwardly, that is; the distance between the outer edges of the side wing is somewhat greater than the width of the back of the pan or basket, as illustrated in Fig. 5.

Referring more particularly to the construction shown in Fig. 1., a layer of concrete to form the ceiling 20 is placed upon the temporary floor to the thickness of about two inches. The inverted pans or baskets are then set down upon this layer of concrete and the projecting ends of the rods 15 which form supporting legs are forced through this layer of concrete so that the baskets are supported by the legs and the sheet metal sides of the baskets are held in position upon the layer of concrete which 20 forms the ceiling. Concrete is then filled in between the sides of the solid baskets as at 23, the side of the pans assuming a substantially perpendicular position, and over the top at 24 to the extent of about two inches. 25 It is to be particularly noted that the $\frac{1}{4}$ " round rods are entirely embedded in the concrete so that they will not only support the roof of each little opening or void, but will not rust out. The concrete also 30 rounds entirely the round rods thereby locking the metal pans or baskets in place.

In the construction shown more particularly in Fig. 2., I provide as a ceiling a composite clay and wire lath structure which 35 can be procured in open market. This clay and wire lath ceiling is composed of wire mesh, the strands of which are covered by clay molded thereupon. In forming this construction, I place the sheet or strips 21 40 of composite clay and wire lath upon the temporary floor. I then place the inverted pans or baskets in position by first pressing the side of the baskets into a substantially vertical position permitting the ends of the 45 wire rods on either side to enter openings in the mesh of the wire lath ceiling. When the pressure upon the side of the basket is released, the sides of the basket spring outwardly and are thereby held to the wire lath 50 ceiling by friction due to the pressure of the protruding ends 13 and 13' of the rods 11 on the strands of the wire lath ceiling. Concrete is then poured into the space 28 between the baskets and over the tops of 55 the baskets at 24 to the extent of about two inches. The lower end of the mass of concrete 23 between the baskets percolates between the strands of the wire lath and thereby completely surrounds the said 60 strands of the wire lath ceiling at 25 and when set holds the wire lath ceiling in place.

Instead of using a single sheet of composite clay and wire lath ceiling, I may utilize separate sheets of galvanized wire lath for 65 each pan or basket to form the ceiling. In

this construction, illustrated in Fig. 3., I place in position upon the temporary floor, strips of galvanized wire lath 22 which are about two inches wider than the distance between the sides of the basket when placed in 70 position. As in the previously described construction, the sides of the basket are pressed in to a substantially vertical position. The ends 13 and 13' of the rods 12 are then inserted in the meshes of the galvanized wire lath at points on either side about an inch from the edge thereof. Upon releasing the pressure from the sides of the pan or basket, the sides spring outwardly and the end of the rods engaging as they do, 75 the meshes of the wire lath hold it to the basket in a stretched condition as shown in Fig. 3. The outer edges of the galvanized wire lath 22 are bent inwardly and upwardly as at 27 and 27' so that when the concrete is 80 filled in around the pans or baskets, the lower end of the concrete inserted between the baskets will pass through the meshes of the free ends of the wire lath at 28 and upon setting will hold the wire lath in place. 85

After the concrete is set, the temporary floor and supporting beams are removed by cutting away the iron stirrups flush with the ceiling in the usual way. The ceiling may be finished by applying plaster in the 90 usual way either to the concrete directly of Fig. 1., or to the wire lath, as the composite clay and wire lath ceiling of Fig. 2. or to the galvanized wire lath ceiling of Fig. 3. While the exact dimensions are not essential, a preferred construction is that in 95 which the thickness of the concrete upon the roofs of the pans or baskets is substantially two inches, the distance between the side of the baskets four inches, the height of the 100 baskets ten inches, and the width thereof sixteen inches. The distances between the wire rods on the baskets are twelve inches and the distance of the first wire rod from the end of the basket at its bend is substantially eighteen inches. The thickness of the 105 concrete forming the ceiling in Fig. 1., is about two inches. The length of the rods extending from either edge of the basket is substantially two inches with the concrete 110 ceiling, and materially less than that with the wire lath ceiling. No

It is to be noted that the wire lath ceiling construction shown in Figs. 2 and 3 as distinguished from the concrete construction 115 of Fig. 1., saves great weight from the supporting beams and girders and therefore there results a saving of weight of material and consequent expense by the use of the wire lath ceiling in the construction shown 120 by me. As a square foot of concrete two inches high weighs approximately sixteen pounds, it is easily seen that if this dead weight can be eliminated, the beams and 125 girders supporting the same can be lighter 130

and a consequent saving of material and expense will result from the use of my improved wire lath ceiling construction.

The illustration is more or less conventional and my invention is not to be limited to details of construction except as particularly referred to in the claims.

Having now described my invention, what I claim as new, and desire to secure by Letters Patent, is:

1. In a fire-proof floor and ceiling construction, having between the floor surface and the ceiling surface a series of voids or openings supported at intervals by concrete partitions, said voids or openings being lined at the top and sides with sheet material having undercut rods or bars secured to said material and projecting bodily therefrom upon the upper surface thereof, the concrete composing the floor and the partitions remaining entirely upon the upper surface of the sheet material and completely surrounding said rods or bars.
2. In a fire-proof floor and ceiling construction, having between the floor surface and the ceiling surface, a series of voids or openings separated at intervals by concrete partitions, said voids or openings being lined at the top and sides with sheet ma-

terial having round rods or bars secured to said material and projecting bodily therefrom upon the upper surface thereof, the concrete composing the floor and the partitions remaining entirely upon the upper surface of the sheet material and completely surrounding said rods or bars.

3. In a fire proof floor and ceiling construction having between the floor surface and the ceiling surface, a series of voids or openings separated at intervals by concrete partitions, said voids or openings being lined at the top and sides with solid sheet metal, having rods or bars secured thereto upon the upper surface thereof and projecting bodily therefrom the ends of said rods or bars extending beyond the edges of the sheet metal pans or baskets a distance substantially equal to the thickness of the ceiling, the linings being held in place by means of the concrete surrounding the rods or bars.

In witness whereof I have hereunto set my hand at the borough of Manhattan, city and State of New York, this 8th day of September, 1914.

ERNEST MERRICK.

In presence of—

ISABEL R. RICHARDS,
JOHN J. RANAGAN.
